UNITED STATES PATENT OFFICE.

GEORGE CLARK EDWARDS, OF BRIDGEPORT, CONNECTICUT, ASSIGNOR TO
THE HOLMES & EDWARDS SILVER COMPANY, OF SAME PLACE.

DESIGN FOR A SPOON.

SPECIFICATION forming part of Design No. 19,770, dated April 22, 1890.

Application filed January 22, 1890. Serial No. 337,754. Term of patent 14 years.

To all whom it may concern:

Be it known that I, GEORGE CLARK EDWARDS, a citizen of the United States, residing at Bridgeport, county of Fairfield, and 5 State of Connecticut, have invented a new and useful Design for Orange-Spoons, of which the following is a specification.

The design relates more especially to the form of the bowl of an orange-spoon, and is 10 illustrated in the accompanying drawings, in which—

Figure 1 is a perspective view of a spoon embodying my design, and Fig. 2 is a face view.

15 The leading feature of the design is the shape of the bowl A of the spoon, which has two nearly-straight side edges xx , converging toward the tip y , which is rounded, and two

nearly-straight back edges yy , connected by curves w with the stem a of the handle B and 20 by other curves v with the side edges xx , so that the bowl is long in proportion to its width and approximates a triangle in outline except at the corners. Any suitable handle may be used in connection with the bowl. 25

What I claim is—

The design for a spoon the bowl of which has converging sides, as shown and described.

In testimony whereof I have signed my name to this specification in the presence of 30 two subscribing witnesses.

GEORGE CLARK EDWARDS.
